(57) **CLAIM**

The ornamental design for a “connector plug for game machine”, as shown and described.

DESCRIPTION

FIG. 1 is a front elevational view of a connector plug for game machine, the rear elevational view being a mirror image thereof;

FIG. 2 is a top plan view thereof;

FIG. 3 is a bottom plan view thereof;

FIG. 4 is a right side view thereof; and,

FIG. 5 is a left side view thereof.
